(72) Inventor: **James Vogt**, San Bruno, CA (US)*Primary Examiner* — Ian Simmons*Assistant Examiner* — Richelle G Shelton(73) Assignee: **salesforce.com, inc.**, San Francisco, CA (US)(74) *Attorney, Agent, or Firm* — Sterne, Kessler, Goldstein & Fox P.L.L.C.(**) Term: **14 Years****(57) CLAIM**(21) Appl. No.: **29/473,065**

The ornamental design for a display screen or portion thereof with animated graphical user interface, as shown and described.

(22) Filed: **Nov. 18, 2013****DESCRIPTION**(51) **LOC (10) Cl.** **14-04**

FIG. 1 is a front view of a display screen or portion thereof with animated graphical user interface showing the first image in the sequence showing my new design;

(52) **U.S. Cl.**

FIG. 2 is a second image thereof; and,

USPC **D14/488**

FIG. 3 is a third image thereof.

(58) **Field of Classification Search**

The broken line showing of the display screen and of portions of the graphical user interface forms no part of the claimed design.

USPC D14/485-495

The appearance of the animated images sequentially transitions between the images shown in FIGS. 1 through 3. The process or period in which one image transitions to another forms no part of the claimed design.

CPC G06T 13/00; G06T 13/80; G06F 3/04845; G06F 3/04847
